UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

REMOVABLE PLATEN SUPPORT.

Application filed July 19, 1924. Serial No. 726,907.

This invention relates to mechanism for retaining the platen in position on a typewriter carriage, and has for its object the provision of such retaining means which shall permit ready removal of the platen.

The invention is exemplified in the combination and arrangement of parts shown in the accompanying drawings and described in the following specification, and it is more particularly pointed out in the appended claims.

In the drawings,—

Fig. 1 is a front elevation with parts broken away of a portion of a typewriter carriage showing one embodiment of the present invention.

Fig. 2 is a section substantially on line 2—2 of Fig. 1.

Fig. 3 is a transverse section adjacent the support at the opposite end of the carriage from that shown in Fig. 1.

Fig. 4 is a view looking from the right in Fig. 3.

Figs. 5 and 6 are perspective views showing details of construction.

Fig. 7 is a section substantially on line 7—7 of Fig. 5.

Referring first to Figs 1 and 2, the numeral 10 designates an upright supporting plate at one end of a platen carriage in which a platen shaft 11 is journaled. The shaft 11 has a ratchet wheel 12, which may be rigidly held thereon and by means of which line spacing movement is imparted to the platen 13. A pawl supporting bracket 14 is pivoted on a stud 15 which is fixed to the plate 10 by a nut 16. Pivot screw 17 is carried at the upper end of the bracket 14 and a pawl 18 is pivotally mounted on the screw 17. The bracket 14 carries an offset ear 19 which overlies a spring 20 interposed between the ear 19 and the pawl 18 for pressing the pawl into engagement with the ratchet wheel 12. The bracket 14 is oscillated upon its pivotal support 15 by a link 23 connected with the pivot screw 17 at one end and provided with a laterally extending ear 24 at its opposite end, the ear 24 being pivoted on a bolt 25 which extends through the end of an arm 26 of a bell crank lever 27 by means of which the link 23 is operated to cause the pawl 18 to rotate the ratchet 12 for line spacing. The bell crank 27 is pivotally mounted on a bracket 28 supported on the plate 10 by

screws 29. When the bell crank 27 is oscillated the pawl 18 will be swung about the pivot 17 as a center, which gives a somewhat larger radius than the radius of the ratchet wheel 12. The pawl 18 will, however, remain in engagement with the ratchet teeth for the limited movement imparted thereto and will move upon its pivot 17 a sufficient amount to compensate for the differences in radii between the ratchet wheel 12 and the supporting bracket for the pawl. The arc through which the pawl moves is limited by an adjustable stop screw 30 carried by the plate 10. When the pawl strikes the screw 30 further angular movement of the lever 27 on its bracket 28 will be prevented so that further pressure on the lever arm 27 will carry the carriage to the right in the usual manner.

It should be noted that instead of a circular opening in the plate 10 for the platen shaft an elongated slot 31 is provided, the slot being open at its top to permit the platen to be lifted upwardly from its seat in the plate 10. The pawl supporting bracket 14 and associated parts are all mounted on the plate 10 independently of the platen shaft so that they will not interfere with the removal of the platen and yet will be in position to operate when the platen is replaced. While the platen is being removed the lever 27 is swung into position to carry the link 23 to its rearmost position, thus moving the upper end of the bracket 14 out of the path of the platen shaft. To retain the platen in position for operation, a detent hook 32 is provided, which is shown in perspective in Fig. 6. The hook 32 is pivoted upon the screw 15 and has a bearing surface 33 formed on an are struck from the axis of the screw 15. The hook 32 may be held in a plurality of angular positions by a detent roller 34, shown in Figs. 5 and 7. This roller is movable vertically in slots 36 provided in the upper end of the hook 32, the roller being pressed downwardly by a spring 38, the ends of which bear beneath a bent-over portion 39 of the hook 32, while the central portion rests upon the roller 35. A finger-piece 40 engages the ends of the roller 35 to facilitate withdrawing the roller from notches 41, 42 and 43 provided in the edge of the plate 10. The hook 32 is provided with an offset stop 44 positioned in the path of a down-

wardly extending finger 45 on the pawl 18. A spring 46 is connected with an arm 47 on the lower end of the pawl supporting bracket 14 so that an abutment face 48 of the bracket is firmly held against the stop 44. The stop 44 will at the same time hold the nose of the pawl 18 away from the ratchet wheel 12 when the bracket 14 is in its forward position as shown in Fig. 2.

When the lever 27 is operated the bracket 14 will move away from the stop 44 and permit the pawl 18 to engage the ratchet wheel 12. The amount of movement of the pawl while in engagement with the teeth of the ratchet wheel will depend upon the position of the stop 44. In the position shown in Fig. 2 sufficient movement is permitted to provide for single spacing. If, however, the detent roller 35 is brought forward into notch 42, sufficient movement of the pawl 18 will be permitted to produce double spacing of the paper. When the roller 35 is brought into the notch 41 the contact face 33 of the hook 32 will be moved entirely free from the shaft 11 so that the platen may be lifted from its bearing.

The carriage plate 50 at the opposite end of the carriage from the plate 10 is provided with a notch 51 open at its top to permit removal of the end of the platen shaft journaled in this plate. In order to properly align the platen it is desirable to be able to shift the bearing for the right hand end of the platen shaft. For this reason the bearing slot 51 is made somewhat larger than the diameter of the platen shaft and a supplemental bearing plate 52 is mounted on the plate 50 and provided with a bearing seat for the shaft 11. The plate 52 is held to the plate 50 by a bolt 53 having an eccentric shoulder 54 journaled in the plate 10. A nut 55 is threaded on the bolt 53 to lock the shoulder 54 in any position of adjustment to which it may be turned. Since the bolt 53 accurately fits in an opening in the bearing plate 52 it will be apparent that the plate 52 may be shifted vertically by rotating the eccentric shoulder 54 on the bolt 53. A locking screw 55 extends through an opening 56 in the plate 50 and is threaded into the upper portion of the plate 52 in order to lock the plate 52 in its various positions of adjustment. The opening 56 is made elongated to permit the plate 52 to be swung upon the bolt 53 as a pivot and it is also made sufficiently wide to permit vertical movement of the plate 52. It will thus be seen that the bearing for the shaft 11 may be adjusted in any direction to properly align the shaft. In order to retain the shaft in its bearing a hook bracket 57 is pivoted at 58 on the plate 52. This bracket is provided with a bearing face 59 formed on an arc struck from the axis of the pivot 58 to permit the hook to be swung from full to

broken line positions in Fig. 3. A stop 60 strikes the edge of the plate 52 to limit the backward movement of the hook. The hook may be provided with a projection 61 arranged to engage the front edge of the plate 52 to hold the hook in its active position and to engage the depression 53 in the plate 52 to retain the hook in its inactive position.

I claim:

1. The combination with a platen shaft, of an upright plate having an open seat therein for receiving said platen shaft, a ratchet on said platen shaft, a bracket pivotally mounted on said platen carriage plate eccentric to said shaft, a pawl mounted on said bracket for engaging said ratchet wheel, and a limit stop for said pawl, said stop being pivoted on said plate independently of said shaft and arranged to limit movement of said bracket and pawl about the pivotal mounting of said bracket.

2. The combination with a platen carriage shaft, of an upright carriage plate having an upwardly open seat therein for receiving said shaft, a ratchet wheel on said shaft, a pawl for operating said ratchet wheel, a bracket for supporting said pawl, a pivotal support for said bracket mounted on said plate below said platen shaft seat, and a stop mounted on said pivotal support for controlling the movement of said pawl.

3. The combination with a platen shaft, of a platen carriage plate having an open seat therein, ratchet mechanism for rotating said platen shaft, a lever for operating said ratchet mechanism, a detent pivoted on said plate for retaining said shaft in said seat, and a stop connected with said detent for limiting the movement of said ratchet mechanism and thus limit the range of movement of said lever.

4. The combination with a platen and a platen shaft, of a platen carriage plate having an open seat therein for receiving said shaft, a bracket pivoted on said plate eccentric to said shaft, a ratchet wheel mounted on said shaft, a pawl carried by said bracket for operating said ratchet wheel, a detent pivoted on said plate concentric with the pivot for said bracket, and a stop connected with said detent for limiting the movement of said pawl.

5. The combination with a platen and a platen shaft, of a support having an open seat therein for said shaft, ratchet mechanism for rotating said shaft, an adjustable stop for controlling the movement of said ratchet mechanism, a detent for retaining said shaft in said seat, and a common support for said detent and stop pivoted on said platen support.

6. The combination with a platen shaft, of a support having an open seat for said shaft, ratchet mechanism for rotating said shaft, a stop for controlling the movement of said

- ratchet mechanism, means for holding said stop in adjusted positions, a detent for retaining said shaft in said seat, said detent being movable with said stop and arranged to hold 5 said shaft in said seat for the adjusted positions of said stop but movable into an additional position to permit removal of said shaft from said seat, said stop holding means comprising a spring held member for engaging spaced openings in said support, and 10 a finger piece connected with said detent and stop and engaging said spring held member to release said spring held member and shift said detent and stop.
- 15 7. The combination with a platen shaft, of spaced supports therefor having open seats to permit removal of said shaft therefrom, and an adjustable bearing mounted on one of said supports to facilitate alignment 20 of said platen shaft, said bearing comprising a plate having a shiftable pivotal support, and means for securing said plate in different positions of adjustment.
- 25 8. The combination with a platen shaft, of a pair of supporting plates for said shaft, one of said plates having an opening therein of greater diameter than said shaft and having 30 a supplemental bearing plate adjustably mounted thereon having an opening therein arranged to fit said shaft and fix the position of the axis thereof to facilitate alignment of said shaft and means for fixing said supplemental bearing plate in different positions of adjustment.
- 35 9. The combination with a platen shaft, of a pair of spaced bearing plates having open seats therein, one of said plates having

a supplemental bearing plate pivotally mounted thereon, the pivotal mounting of said plate being provided with means for 40 adjusting said plate transversely of the axis thereof.

10. The combination with a platen and a platen shaft, of spaced bearing plates therefor, one of said plates having an open seat 45 therein of greater diameter than said shaft, a supplemental bearing plate adjacent said open seat, an eccentric pivot for said plate, and means for locking said plate in adjusted positions.

11. The combination with a platen and a platen shaft, of a pair of spaced bearing plates having open seats therein for receiving said shaft, one of said plates having a supplemental bearing plate secured thereto 55 and adjustable thereon for alignment, and a detent pivotally mounted on said supplemental plate.

12. The combination with a platen and a platen shaft, of a pair of spaced bearing 60 plates having open seats therein, a supplemental bearing plate secured to one of said first-mentioned bearing plates, an eccentric pivot for said supplemental bearing plate, means for locking said supplemental bearing 65 plate in adjusted positions, and a detent for retaining said shaft in said supplemental bearing plate, said detent being pivoted on said supplemental bearing plate to move into and out of retaining position.

In testimony whereof I have signed my name to this specification on this 17th day of July, A. D. 1924.

OTTO A. HOKANSON.
